(57) **CLAIM**

The ornamental design for a vent for a soffit panel with top openings, as shown and described.

DESCRIPTION

FIG. 1 is an isometric view of a vent for a soffit panel with elongated top openings according to an exemplary embodiment;

FIG. 2 is a top plan view of the vent for a soffit panel with top openings shown in FIG. 1;

FIG. 3 is a bottom plan view of the vent for a soffit panel with top openings shown in FIG. 1;

FIG. 4 is a bottom-end elevation view of the vent for a soffit panel with top openings shown in FIG. 2;

FIG. 5 is a top-end elevation view of the vent for a soffit panel with top openings shown in FIG. 2

FIG. 6 is a left-side elevation view of the vent for a soffit panel with top openings shown in FIG. 2

FIG. 7 is an enlarged detail of FIG. 6; and,

FIG. 8 is a right-side elevation view of the vent for a soffit panel with top openings shown in FIG. 2.
